UNITED STATES PATENT OFFICE.

CLARENCE WALLACE TAYLOR, OF JANEVILLE, WISCONSIN.

FOUNTAIN-PEN.

SPECIFICATION forming part of Letters Patent No. 340,166, dated April 20, 1886.

Application filed February 12, 1886. Serial No. 191,707. (No model.)

To all whom it may concern:

Be it known that I, CLARENCE WALLACE TAYLOR, of Janesville, in the county of Rock and State of Wisconsin, have invented certain new and useful Improvements in Fountain-Pens; and I do hereby declare the following to be a full, clear, and exact description of the invention, such as will enable others skilled in the art to which it appertains to make and use 10 the same.

My invention relates to that class of pens in which the ink is contained within the body of the pen-holder and is fed therefrom to the pen-point, during the act of writing, through 15 suitable ducts or channels.

My invention relates more particularly to that class of fountain-pens which are designed to receive gold, steel, or other metal pens of the usual forms. As heretofore constructed, 20 these pens have been seriously defective, owing to the fact that any sediment of foreign matter in the ink enters the capillary tubes or ducts and either partially or wholly clogs them, whereby the flow of ink is either entirely 25 stopped or is rendered irregular, very scanty, or very excessive. Moreover, when these pens are first filled, or when they have been unused for a short time, their operation is very unsatisfactory, owing to the dryness of the working 30 parts and particularly of the pen itself. When steel pens are used with fountain-pens, as heretofore constructed, such pens rapidly corrode, and hence great waste ensues.

The objects of my invention are to produce a 35 fountain-pen which shall be prompt and certain in its action and in which the flow of ink shall be uniform at all times, which shall meet the demands of rapid writing and shading, and the ducts and channels of which shall be 40 free from clogging, while the pen itself, if of corrodable metal, shall be protected against corrosion when the pen is not in use.

To the above purposes my invention consists, first, in an adjustable plug provided with 45 a large ink-channel extending nearly the entire length of the plug and communicating at its upper end with the ink-reservoir and at its lower end through a small ink-channel with a capillary feeder directly beneath the pen 50 proper, the upper interior surface of the conduit being formed with one or more grooves

adapted to transmit ink by capillary action from the reservoir and conduit to the small ink-channel without permitting the entrance into the latter of any sediment or other foreign matter, as hereinafter described and 55 claimed.

My invention further consists in the combination, with the large ink-conduit having the groove or grooves in its upper interior surface 60 and the small ink-channel leading therefrom, of a capillary feeder located directly beneath the pen proper, of an ink-well located in the lower end of the adjustable plug and in communication with the pen through a second 65 small ink-chamber or capillary feeder, said well serving as a reservoir to meet the demands of rapid writing and shading, as hereinafter described and claimed.

My invention further consists in certain peculiar and novel features of construction and arrangement relating to the cap for protecting the pen proper from corrosion, the attachment of the pen proper to the holder, and the attachment and removal of the adjustable plug, 70 as hereinafter described and claimed.

In order that my invention may be fully understood, I will proceed to describe it with reference to the accompanying drawings, in 75 which—

Figure 1 is a longitudinal vertical section of my improved fountain-pen. Fig. 2 is a detached view of the adjustable plug, showing the same in side elevation. Fig. 3 is a longitudinal horizontal section of the adjustable 80 plug on the line 3 3 of Fig. 2, looking upward at its interior surface. Fig. 4 is a vertical cross-section on the line 4 4 of Fig. 2. Fig. 5 is a vertical cross-section on the line 5 5 of Fig. 2. Fig. 6 is a view in elevation of the 85 upper side of the adjustable plug. Fig. 7 is a longitudinal section of the cap. Fig. 8 is a detached view of the upper side of the socket-piece, showing the manner of attaching the pen proper. Fig. 9 is a sectional view on the 90 line 9 9 of Fig. 8. Fig. 10 is a longitudinal section of the adjustable plug, showing a modification of the invention.

In the said drawings, A designates the body or holder of the pen, which is hollow, as 95 shown, to receive the charge of ink, and thus to serve as a reservoir for supplying ink to the 100

pen proper. The upper end of this body or holder is reduced, as shown at *a*, to receive the hollow cap *A'*, which is provided with a perforation, *a''*, the purpose of which will appear in the ensuing description. The lower end of the holder *A* is internally screw-threaded to receive the reduced and externally-threaded portion *c* of a socket-piece, *C*. This socket-piece is formed with an annular shoulder, *c'*, which forms a tight joint with the lower end of holder *A*, and upon its upper side, at the lower end thereof, said socket-piece is cut away, as shown at *c''*, to a depth corresponding with about the thickness of an ordinary gold or steel pen, *D*, the width of this cut being at its upper part somewhat less than the width of the pen. As shown in Fig. 8, the lateral margins of this cut or recess are slightly undercut to receive and hold the lateral edges of the pen, while the end margin of said cut is similarly undercut to receive the upper end of the pen. (See Fig. 1.) The purpose of thus attaching the pen proper is to render it capable of a slight upward spring when pressed upon the paper in the act of writing, and the result of this movement of the pen proper will appear from the ensuing description.

E designates the adjustable plug. At its upper or inner end this plug is of cylindrical form, so as to fit tightly within the socket-piece *C*, and this cylindrical formation extends about one-fourth of the entire length of the plug, so that said plug may be inserted to a greater or less extent within the socket-piece, in order that the outer end of the plug may assume the required position relative to the nibs of longer or shorter pens.

e designates the large ink-conduit, which begins at the upper or inner end of the plug, at which point said conduit communicates with the interior of the holder *A* and extends longitudinally of the plug, terminating near the outer or lower end thereof.

e' designates a small duct or ink-channel, which opens from above the lower end of conduit *e*, and extends at right angles therefrom to the upper side of the plug. Beginning near the lower or outer end of the plug, in its upper surface, inclined downward toward the upper or inner end of said plug through a distance corresponding with about the length of the body portion of an ordinary pen, exclusive of its nibs, there is formed a groove, *e''*, which I term a "capillary feeder," and which extends from near the lower or outer end of the plug upward nearly to the inner or upper end of the pen proper when the latter is in position. This groove or feeder preferably diminishes in width and depth toward its lower end, near which it communicates with the conduit *e* through the small ink-channel *e'*.

When the pen *D* is in position upon the holder, the groove *e''* is covered by about three-fourths of the body portion of said pen, and it will be seen that the ink in conduit *e* is drawn through the channel *e'* by capillary action, and that the groove *e''* and the body por-

tion of pen *D* draw the ink from channel *e'* into the groove *e''* by capillary action, so that said groove is kept filled with ink as long as there is any ink in the reservoir.

When the pen is not being used, there is no waste of ink, because the pen proper presses down upon the top of the plug and prevents any flow of ink; but as soon as the pen proper is pressed upon the paper in the act of writing, its slight upward movement, previously alluded to, allows the ink to flow down to the nibs of the pen.

In the upper surface of the conduit *e* are formed one or more longitudinal grooves, *e'*, three being shown, said grooves extending from the upper or inner end of the conduit to the lower opening of the channel *e'*. These grooves are to prevent the entrance of any sediment or foreign matter which may be in the ink into the channel *e'* or groove *e''*, and this result is accomplished by the capillary action of said grooves *e'*, whereby they draw up the ink from the conduit, leaving the sediment upon the lower surface thereof, and conduct the pure ink to the channel *e'*. Thus it is impossible for any sediment to pass through the channel *e'*.

In order to provide for the sudden increase in the flow of ink demanded by shading and the constant increase in such flow required by rapid writing, I form a cavity, *e'*, in the lower end of plug *E*. This cavity communicates with the upper surface of the plug, at the lower end thereof, through a capillary channel, *e''*, as shown. Thus when the pen is pressed hard upon the paper, as in shading, the upward movement of the pen proper opens the outer end of channel *e''* and permits an increased flow of ink, while during rapid writing the ink-well *e'* affords a constant increase of ink to the pen. This ink-well receives its ink when the pen proper is pressed upon the paper, the upward movement of the pen proper permitting a portion of the ink flowing from groove or feeder *e''* to enter the channel *e'* and thus flow into the well *e'*.

The air necessary to fill the vacuum created in the reservoir of holder *A* by the outflow of ink enters said reservoir from beneath the pen proper, such air passing through the channel *e'* and conduit *e*. Thus the air entering the reservoir is compelled to pass through a considerable body of ink, and but a small amount of air enters at any given time, so that the displacement will be gradual, all spasmodic action will be avoided, and a constant uniform flow of ink will be insured.

When the cap *A'*, before mentioned, is placed upon the lower end of the pen, the ridge or projection *a'* thereof fits over the slit and hole of the pen proper, thus shutting off the air from contact with the ink in the capillary feeder and preventing evaporation, and also holding the pen proper firmly against the plug *E*. The perforation *a''* permits the escape of air from within the cap when the latter is being placed upon the lower end of the pen, so

that the air cannot be forced into the reservoir, thus also preventing the objectionable action of air upon the ink and pen.

In order to lessen the weight of the plug E 5 its lower end is beveled off upon the under side, and a ridge or backbone, e^6 , is formed thereon, which extends the surface of pressure of the socket-piece C. A projection, e^7 , is formed upon the lower part of ridge e^6 , to afford proper hold in inserting, removing, or adjusting plug E.

By virtue of the construction above described the pen may be used until the last drop of ink has been fed from the reservoir, 15 the flow of ink will be automatic, constant, and uniform, and as there are no valves or movable parts to become clogged the pen will retain its usefulness and remain in working order until the ink-reservoir is emptied.

20 The capillary feeder is instantly filled whenever the pen is closed down upon the plug, so that the pen is always ready for use, that part of the pen proper which must be wet with ink before the pen can be used being always kept 25 wet by the feeder. When the pen is pressed upon the paper, the ink begins instantly to flow, so that no jolting of the pen is required to bring down the ink.

In Fig. 10 I have shown a modification of 30 my invention, wherein the ink-well e^4 and the channel e^5 are dispensed with, while the ink-conduit e , the channel e' , and the feeder e'' are widened or extended downward nearer to the point of the pen. In this construction, however, no material departure is made from the 35 essential spirit of my invention.

Having fully described my invention, what I claim as new, and desire to secure by Letters Patent, is—

40 1. The combination, with an ink-reservoir, of a plug having an ink-conduit, an ink-well located on the upper face of the plug below the discharge end of the ink-conduit, and a capillary feeder in open communication with the

discharge end of the conduit, substantially as 45 set forth.

2. In a fountain-pen, an ink-conduit communicating with the reservoir and provided with superposed channels for conducting ink from the reservoir and conduit by capillary 50 action separating the sediment from such ink, substantially as set forth.

3. In a fountain-pen, a plug having a longitudinal ink-conduit communicating with the ink-reservoir and also with the upper surface 55 of the plug, and provided with longitudinal capillary channels communicating with the ink-duct, said channels serving to separate the ink from its sediment and to convey the ink to its outlet, substantially as described. 60

4. In a fountain-pen, a plug having a longitudinal ink-conduit communicating with the reservoir and with the upper surface of the plug, capillary channels extending longitudinally of said duct in its upper surface, and a 65 capillary feeder formed in the upper surface of said plug and communicating with the ink-duct, substantially as and for the purpose set forth.

5. The combination, with a reservoir, a 70 socket-piece secured within the open end thereof and having the cut e^8 for holding the pen proper, of the adjustable plug E, having a longitudinal conduit, e , the channels $e' e^3 e^5$, a feeder, e^2 , on the upper surface of the plug 75 and in communication with the conduit, the well e^4 , also in communication with the conduit, and the ridge e^6 , and the cap A', having the projection a' and perforation a^2 , substantially as and for the purpose set forth. 80

In testimony whereof I have signed this specification in the presence of two subscribing witnesses.

CLARENCE WALLACE TAYLOR.
